CHARLES S. BUSHNELL, OF ROCHESTER, NEW YORK, ASSIGNOR TO GENERAL RAILWAY SIGNAL COMPANY, OF ROCHESTER, NEW YORK.

TRAIN CONTROL.

Application filed October 25, 1923. Serial No. 670,701.

This invention relates to automatic train control systems, and more particularly to systems of the intermittent inductive type.

In providing apparatus for automatically controlling a train in accordance with traffic conditions ahead, it is desirable to be able to automatically restrict the speed of a train in a caution block if the train is to be brought to a predetermined low speed or to a stop before reaching the end of such a block, and to enforce a low limiting speed throughout the following or danger block providing traffic conditions have not cleared up in the meantime. On account of the speed the train may be running, weather conditions, the collection of ice and snow and for various other reasons, it is found difficult to transmit control influences by physical contact between vehicle carried devices and cooperating devices located along the trackway. In providing means for transmitting control influences which are intended to restrict the movement of the train it is highly important that such influences be invariably transmitted under danger traffic conditions ahead, regardless of the speed of the train; whereas the transmission of restoring control influences is not necessarily effective at all speeds, because the failure to receive a restoring or resetting influence merely causes the movement of the train to be unnecessarily restricted and therefore is on the side of safety.

With the above and other considerations in mind the principal object and purpose of the present invention contemplates the provision of means to transmit restrictive control influences from the trackway to a moving vehicle inductively by the employment of alternating current and effective at all speeds and which means is constructed on the normally closed circuit principle so that the failure of a circuit will cause the transmission of a control influence and restrict the movement of the train regardless of traffic conditions ahead, and to provide means for transmitting a restoring influence which is dependent on a source of direct current energy and possibly is effective only for speeds above a predetermined low speed and which is constructed entirely on the open

circuit principle so that the failure of a circuit prevents the transmission of a restoring control influence, thereby also functioning on the side of safety.

More specifically it is proposed to provide a car-carried core in which an alternating magneto-motive-force is set up near one end of the core by a primary coil, to provide two secondary coils, one near said primary coil and one a considerable distance from said primary coil which are connected so that the voltages induced by reason of said primary coil oppose each other and in which the voltage in the secondary coil nearer the primary coil predominates, and to connect the circuit including the two secondary coils in series to a direct current relay through an intervening rectifying device whereby the relay is maintained energized by unidirectional current derived from the predominating secondary coil; to provide an inert trackway device which is adapted to reduce the reluctance of the magnetic circuit including said car-carried core upon passage of the car-carried core by said trackway device under predetermined traffic conditions ahead, whereby flux is diverted from leakage paths through the distant secondary coil causing a higher opposing voltage in the circuit and causing deenergization of said relay.

Other objects, purposes and characteristic features of the invention will appear as the description thereof progresses.

In describing the invention in detail reference will be made to the accompanying drawings in which:—

Fig. 1 illustrates conventionally one arrangement of trackway circuits and devices embodying the present invention; and

Fig. 2 shows diagrammatically the circuit arrangement of the car-carried apparatus in which the various devices have been shown conventionally.

Track equipment.

Referring to Fig. 1 of the drawings, there has been shown a trackway of the usual construction including the rails 1, which are divided by insulating joints 2 into blocks in the usual manner, the block I and the adja-

cent ends of two other blocks H and J having been shown; since the various blocks are the same like parts thereof have been given the same reference characters with distinctive exponents. Each of the blocks is provided with the usual trackway battery 3 at the exit end thereof and a track relay 4 at the entrance end, the direction of traffic being from left to right as indicated by the arrow.

At the entrance end of each block is preferably provided a wayside signal of the usual type; although these signals may be of the color light, position light or semaphore type, for convenience semaphore signals Z have been shown conventionally without illustrating their well-known control devices and circuits, these devices and circuits being well-known by those skilled in this particular art. In addition to the track relay 4 at the entrance to each block there is provided a line relay 5, which is under normally clear traffic conditions energized by a circuit including the front contact 6 of its associated track relay and the front contact 7¹ of the track relay of the block next in advance, so that the line relay 5 is energized, providing both the corresponding block and the block next in advance are unoccupied. This circuit receives its energy from a suitable source, such as a battery having terminals one of which has been designated B, the other terminal being connected to a common return wire C. This source of energy may comprise any number of batteries as for instance one for each block or may consist of a transmission line for supplying a series of blocks.

On the right hand side of the trackway and just before the entrance to each block is provided a knock-down element KD, comprising a magnetizable core 8 of general U-shape terminating in enlarged pole pieces 9 having a coil 10 on the back yoke thereof, which is normally closed in a circuit of low resistance by the front contact 11 of the line relay 5.

In series with the track circuit of the block in the rear, that is, in series with the track battery 3 is connected a relay DL which for convenience may be called a series relay. This relay DL is designed so that its front contact 12 is, under clear traffic conditions, in the lower or deenergized position. If, however, a train occupies the track circuit including this relay DL sufficient current is caused to flow in the track circuit in question to effectively energize this relay DL and close its front contact 12. If desired this relay may be designed so that it will not assume its energized condition until a train very closely approaches the exit end of the block, it being understood that the track circuit current gradually increases as the train approaches the track battery 3.

On the left side of the trackway is provided a similar track element RS conven-

iently called the restoring or resetting track element, which comprises a core 15 of general U-shape terminating in enlarged pole pieces 16 and having a coil 17 on the back yoke thereof. As is obvious from the circuit shown in Fig. 1 of the drawing this coil 17 is energized by current derived from the battery 18, or other suitable source of energy, providing the block at the entrance to which the element RS is located is unoccupied and the series relay DL is in the energized condition, but is closed in a circuit of low resistance when said block is occupied and the series relay DL is in its energized condition, for reasons more clearly pointed out in connection with the operation of the system. In other words, the knock-down element KD has its coil closed in a circuit of low resistance under clear traffic conditions but has its coil open under danger conditions, whereas the restoring or resetting element RS has its coil closed in a circuit of low resistance under danger traffic conditions in the block at the entrance to which it is placed but has its coil energized by a source of electrical energy if said block is clear providing the series relay DL is in its energized condition.

Car-carried devices.

Referring to Fig. 2 of the drawing there has been conventionally illustrated a railway vehicle by the axles 25 and 26 and associated car wheels 27 and 28. In order to provide the proper control for the car-carried apparatus to be described hereinafter regardless of whether the car or locomotive is traveling pilot or tender first, suitable automatic switching apparatus is provided to make the proper circuit changes if the direction of travel of the vehicle is reversed.

This switching apparatus comprises a double-throw circuit controller comprising a long operating rod 30 slidably supported by a bearing boss 31. This rod 30 has connected thereto but insulated therefrom a series of switch blades 32-33-34-35-36-36^a-35^a-34^a-33^a and 32^a and has one end pivotally connected to an arm 37^a integral with a ring 37 pivotally mounted on the axle 26 of the vehicle and is frictionally held to the axle by the conventional friction clutch shown. Any other type of friction clutch may of course be used, if desired. Adjacent the ring 37 is provided the friction clutch comprising an arcuate member 39 which is lined with the usual brake lining for causing frictional engagement between the ring 37 and the shaft 26. This member 39 is provided with an extension slidably supported in the lug 41 projecting from the arm 37^a, and this arcuate member or brake-shoe 39 is urged against the axle 26 by the compression coil spring 42 surrounding the extension 40. With the railway vehicle mov-

ing from left to right in the normal direction of traffic, the switch blades assume the position as shown in the drawing by reason of the frictional engagement between ring 37 and the axle 26, the movement of this arm 37^a being limited by one or the other direction of the stops 43 depending on the direction of movement of the vehicle.

At a convenient and accessible place on the vehicle is mounted a control relay CR, which is normally energized by a pulsating direct current in a manner more clearly described hereinafter. This relay CR is preferably of the quick acting direct current type and in practice preferably includes a pivotally supported and well-balanced armature which controls suitable circuits as shown. On account of the comparatively light armature used which is pivotally supported about its center of mass this relay is substantially immune to jars and vibration, and by reason of its light construction very quickly responds to a sudden change in the energizing current of the relay. On the car is also provided a restoring or pick-up relay PR, which is of construction similar to the control relay CR, which for reasons given in connection with the control relay CR is quick acting and immune to vibratory disturbances.

The car-carried apparatus illustrated in Fig. 2 also includes a suitable rectifying device. Although this device may be of the electrolytic or other suitable type, it has been conventionally shown as comprising a rectifier of the thermionic type, and in the particular manner shown comprises an audion A provided with the usual plate 45, a grid 46 and a filament 47.

In order to provide on the railway vehicle a suitable mechanism for controlling a train through a caution block so as to enforce a reduction in the speed to a certain limit by the time it reaches the end of the block, and in order to limit the speed of the train through a following block unless traffic conditions have become clear, a suitable apparatus is preferably provided which may be initiated upon the reception of a knock-down or restrictive control influence and which may be restored by the reception of a resetting or restoring control influence. For convenience no specific form of speed restricting device for this purpose has been illustrated, but a device for carrying out this function has been conventionally shown by the device K. This device K may abruptly restrict the speed of the vehicle to a predetermined value, or may gradually reduce the permissive speed of the vehicle in accordance with time, deceleration, amount of braking effective or the distance or movement of the train. For example, the device K may comprise mechanism for reducing the permissive speed of the train in accordance with the distance or movement thereof from

the point where a restrictive control influence has been received as illustrated in the patent granted to P. J. Simmen, August 17, 1915, Serial Number 1,150,209.

On the right side of the vehicle illustrated, assuming it to be moving in the direction as indicated by the arrow in Fig. 1, is provided a car element L comprising a core 50 of general inverted U-shape having depending legs terminating in enlarged pole pieces 51. On the rearwardly disposed leg of the core 50 is a primary coil P, which is normally energized by alternating current, and a secondary coil S in which voltage is induced by well-known transformer action. On the other leg of the core 50 is provided a secondary bucking coil SB, which is connected in series with the secondary coil S so that the voltage induced therein is opposite to the voltage induced in the secondary coil S. This car element L is suitably mounted on the truck of a railway vehicle, such as a tender truck, and is preferably supported by initially tensioned springs so that it is under ordinary conditions rigid with respect to the truck, but is adapted to move with respect thereto in cases of severe jars, and the like. This element is so supported that it magnetically cooperates with one or the other of the track elements KD or RS through an intervening air gap depending on whether the vehicle is moving pilot or tender first. On the left hand side of the vehicle is provided a similar car element L^a; this element L^a is identical in construction to the car element L and for convenience like parts have been given like reference characters with distinctive exponents "a."

Car-carried system.

Under normally clear traffic conditions of the car-carried apparatus with the vehicle moving from left to right and the switch blades assuming the position as shown in the drawings the primary coil P of the car element L is energized by a circuit which may be traced as follows:—beginning at a suitable source of alternating current, conventionally shown by the generator G, a wire 53, condenser 54, wire 55, bus bar 56, wire 57, switch blade 34, wire 58, primary coil P, wire 59, switch blade 35, wire 60, bus bar 61, wire 62, back to the alternating current generator G. With this primary coil P energized by alternating current a certain voltage is induced in the secondary coil S by transformer action. This voltage however, is opposed to a slight extent by the voltage induced in the bucking coil SB by reason of the leakage flux passing through this coil SB. The voltage induced in the coil S, however, predominates the voltage induced in the coil SB so that there is a voltage left which produces a current flowing in the following circuit for energizing the control relay

CR:—beginning at the secondary coil S wires 63 and 64, bucking coil SB, wire 65, switch blade 32, wire 66, bus bar 67, wire 68, coil 69 of the control relay CR, wire 70, front contact 71 of the control relay CR, wire 72, the plate 45 and grid 46 to the filament 47 of the audion A, wire 73, bus bar 74, wire 75, switch blade 36, wire 76, back to the secondary coil S. The potential of the secondary coil S predominates over the potential induced in the bucking coil SB and causes a pulsating unidirectional current to flow in the winding 69 of the control relay CR, by reason of the rectifying action taking place in the audion A. The various parts are so designed that the current flowing in this circuit is just sufficient to maintain the control relay CR in its energized condition, so that a slight reduction in this current, possibly because of an increased bucking voltage in the coil SB causes de-energization of this relay. With the control relay CR in its energized condition the speed restricting device K is energized by reason of the circuit including the battery 77 and the front contact 78 of the control relay CR. Under abnormal conditions of the car-carried apparatus certain other circuits are momentarily energized which may be more conveniently described in connection with the operation hereinafter.

Operation.

Clear to caution.—In order to illustrate the operation of the system under various traffic conditions ahead, let us assume that the block J is occupied, or presents dangerous traffic conditions for some other reason, so that its track relay 4¹ is deenergized. Let us further assume that a train is equipped with the car-carried apparatus illustrated in Fig. 2 in its normal clear condition as shown and is moving in the block H in the normal direction of traffic. With the track relay 4¹ deenergized the circuit for the line relay 5 is broken thus deenergizing this line relay, thereby putting the coil 10 of the track element KD in an open circuit. As the train approaches the signal Z, which is now indicating caution, the left hand car element first comes into communication with the resetting track element RS. Since, however, the car-carried apparatus is in its normal condition the operation that takes place at this time need not be considered. After a further short distance of movement of the train the right hand car element L comes into cooperating relation with the track element KD. While the car element L is disposed over the track element KD during its movement along the track the pole pieces 51 of the car element L are momentarily bridged by the core 8 of the track element KD, thereby reducing the reluctance of the magnetic circuit including the car-carried

core 50. This decrease of the reluctance through the core 50 causes a considerable increase in the alternating current magnetic flux passing through the coil SB. This increase of magnetic flux is due to a large extent, it is believed, to diversion of flux from leakage paths. The total flux through the primary coil is maintained substantially constant by reason of the law governing the flow of exciting current to transformers, and the like. Since the amount of flux passing through the coil SB has been considerably increased by reason of the presence of the track element KD, and since, as just explained, the total flux passing the primary coil has not been materially changed, it becomes apparent that the voltage induced in the coil SB is considerably larger whereas the voltage induced in the secondary coil S has been practically unchanged. Further, since the voltage induced in the coil S is no longer capable of predominating over the voltage induced in the coil SB, at least not to an extent to maintain the control relay CR energized, the control relay CR momentarily assumes its de-energized position at the time the car element L is in cooperating relation with the track element KD. This momentary de-energization of the control relay CR causes its front contact 71 to be opened. The opening of this front contact 71 interrupts the energizing circuit for the control relay CR permanently, so that the return of the conditions of the car element to normality will not again energize this control relay. With the control relay CR in its deenergized position the contact 78 assumes its lower position and thereby deenergizes the train control device K and effects a restriction in the speed depending on the construction of this device K. The train may now proceed in block I in accordance with the restriction enforced by the train control device K, thereby bringing the train to a low or minimum speed, or to a stop, by the time it reaches the end of the block I.

Caution to caution.—Let us assume that the train which formerly occupied the block J has advanced out of block J into the next block in advance so that the track relay 4¹ again assumes the energized position. As the train in question reaches a position in the block I at which the car element L^a comes into communicating relationship with the resetting track element RS¹ a restoring control influence is transmitted. This restoring control influence is transmitted by reason of the car element L^a moving over the track element RS¹ while this track element is energized by direct current. The passage of the car element L^a over the energized resetting track element RS¹ causes a rapid building up and breaking down of magnetic flux linking the

coils SB^a and P^a on the core 50^a, so as to cause a single cycle of voltage to be induced in the circuit including these coils, which is similar to a single cycle of alternating electro-motive-force. The induction of this voltage in the coils just mentioned which are connected in series so that their voltages are cumulative, causes a current to flow through the following circuit:—beginning 5
 10 at the primary coil P^a , wire 58^a, switch blade 34^a, wire 80^a, switch blade 33^a, wire 81^a, coil SB^a , wire 65^a, switch blade 32^a, wire 82^a, bus bar 83, wire 84, winding of the re-setting or restoring relay PR , wire 85, bus 15 bar 86, wire 87^a, switch blade 35^a, wire 59^a, back to the primary coil P^a . The flow of an alternating current in the circuit just traced causes the pick-up or restoring relay PR to momentarily assume its energized position, thereby closing its front contact 88 and completing a circuit for the lower winding of the control relay CR and including the battery 89, which circuit may be readily traced in the drawing. The completion of 20 this latter circuit causes the control relay CR to assume its energized position thereby closing its front contact 71, so that the voltage induced in the secondary coil S in the car element L may again maintain this relay CR energized permanently for reasons heretofore given. With the control relay CR permanently energized the contact 78 completes the circuit so as to maintain the train control or speed restricting device K 25 energized whereby the restriction inflicted by this device K while the train was moving through the block I is removed.

Since the train ahead is still in the block next in advance of the block J , as heretofore assumed, the line relay 5¹ is in its de-energized position thereby putting the track element KD^1 in its abnormal active condition. As the train proceeds a little farther its passage by the element KD^1 causes the 30 control relay CR to respond the same as it did when the train entered the block I , thereby again putting the speed restricting device K in its active condition the same as when the train in question moved from a 35 clear into a caution block.

Caution to danger.—Had the train which formerly occupied the block J still been in this block J the front contact 13¹ of the track relay 4¹ would have assumed its 40 lower position thereby completing a circuit of low resistance for the coil 17¹ of the restoring track element RS^1 as soon as the series relay DL became energized, it being assumed that this relay DL assumes its energized position when a train enters a block such as the block I . With the coil of the 45 restoring track element RS^1 closed in a de-energized circuit no voltage would have been induced in the coils SB^a and P^a of the

car-carried element L^a , and consequently 50 the restoring or pick-up relay PR would not have assumed its energized position to pick up the control relay CR , and the train would have been restricted during its movement through the next block, namely the 55 block J ; and if no restoring influence should be communicated at the end of the block J the restriction in the speed of the train would persist.

Clear to clear.—Let us now assume that 60 the train equipped with apparatus as shown in Fig. 2 is moving in the normal direction of traffic in the block H under clear traffic conditions of the blocks I and J , and with the car-carried apparatus in its normal clear 65 condition as shown in the drawings. As the train nears the exit end of the block H the series relay DL will assume its energized position by reason of the increased current flowing in the track circuit of the block H . 70 The energization of this series relay DL , bearing in mind that the track relay 4 is energized, causes the restoring track element RS to be energized. As the car element L^a passes over this track element RS the relay 75 PR is momentarily energized without in any way changing the condition of the car-carried apparatus. After a further short distance of movement the right hand car element L comes into communicating relation 80 with the track element KD . Very little current changes, if any, take place in the upper winding of the control relay CR during the passage of the car element L over the track element KD under this condition, that 85 is, with the coil 10 of the track element KD closed in a circuit of low resistance. One reason whereby this difference in the action 90 of the car-carried apparatus may be accounted for when the car element L passes over a track element having its coil closed in a circuit of low resistance, is, that the coil 10 of the track element acts as a bucking coil 95 thereby preventing to a large extent the passage of flux through the yoke 8 of the track element KD , so that the reluctance of the car-carried core 50 is not materially reduced although it is disposed directly over the core 100 8 of the track element KD . In other words, 105 the presence of a coil closed in a circuit of low resistance surrounding the core 8 greatly resists and opposes the passage of flux through this core, so that the flux passing 110 through the bucking coil SB of the car element L is not materially different even 115 though the car-carried element L is disposed directly over the track element KD in its clear traffic condition.

Disposition of track elements.—The restoring track elements RS is located along the 120 track so that it will be encountered before the knock-down element KD is encountered so that when a train moves from one caution

block into a following caution block the speed restricting device K may be restored to its energized condition and may then again be initiated when passing over the element 5 KD located just beyond the element RS. This feature is specially desirable in systems in which the train control device K is of a cyclic type. For instance, let us assume that a speed restricting device of the type shown 10 in the Simmen patent heretofore mentioned is employed. While the train is passing through one block its speed will be gradually restricted so as to reach a predetermined low speed upon reaching the end of a caution 15 block; if the following block has assumed the caution condition in the meantime the speed restricting apparatus is restored at the restoring track element RS and is again initiated at the knock-down track element 20 KD; so that the speed restriction is removed upon entering the second caution block but the permissive speed is again gradually decreased while the train moves through this second caution block.

25 In the particular circuit arrangement shown the track element KD must be set back into the preceding block far enough so that the first axle of the train does not enter the block before the car element L has 30 passed by the track element KD, because if this were possible the train would restrict itself by dropping the track relay and in turn the control relay CR. If, however, it is desired to restrict the train only after it 35 has passed a certain distance into a caution block, this may be done by controlling the circuit for coil 10 on the track element KD by the track relay of the next block ahead, in the same manner as the line relay controls 40 this coil in the circuit arrangement shown.

Train moving tender first.—Let us now assume that the railway vehicle and car-carried equipment associated therewith conventionally shown in Fig. 2 is turned end for end, 45 so that the axle 26 leads and the axle 25 trails. As the train moves in the normal direction turned end for end as just explained the arm 37^a will be shifted so as to engage the other stop 43 thereby throwing all of the 50 switch blades to the dotted position. By carefully studying Fig. 2 of the drawings, it will be noted that like coils and wires of the car element L and L^a will be interchanged, so that the car element L^a now functions to 55 transmit restrictive control influences instead of restoring influences, whereas the car element L is adapted to receive restoring influences instead of restrictive control influences. In other words, the car-carried relays PR and CR will respond equally as 60 well if the vehicle on which they are mounted moves tender first as when it moves pilot first.

Train moving against the normal direction of traffic.—It sometimes happens that 65 trains are compelled to move against the normal direction of traffic, possibly on account of a wreck, replacement of a bridge, or the like, and for this reason it is desirable to have the car-carried apparatus designed 70 to permit the train to move against the normal direction of traffic. It is, of course, understood that the engineer would be moving his train strictly in accordance with written train orders under this condition, and that 75 he would not rely on the train control apparatus. Let us assume that a train equipped with the car-carried apparatus illustrated is moving against the normal direction of traffic, that is, from right to left, 80 in the block I. With this train moving in the block I the track relay 4 would of course be deenergized. As the train moves across the insulating joints 2 into the block H the series relay DL immediately assumes its 85 energized position thereby closing its front contact 12. Upon further movement of the train into block H the left hand car element L comes into communicating relation with 90 the track element KD. Since, however, the car element L is now connected in the car-carried circuits to function as a restoring element it will not receive a restoring control influence because the track element KD is not energized as would be required. Upon 95 a further movement of the train from right to left into block H the car element L^a comes into communication with the track element RS. No knock-down influences will be transmitted to the car element L^a, which 100 now functions as a restrictive control influence receiving means, because this coil 17 on the track element RS is closed in a circuit of low resistance including the back contact 13 of the track relay 4 and the front contact 105 12 of the series relay DL, so that the car-carried equipment continues to assume its clear traffic condition when the train on which it is mounted moves against the normal direction of traffic over the track apparatus illustrated. Since, as just explained, the car-carried apparatus functions satisfactorily when moving against the normal direction of traffic, that is, cannot receive either restrictive or restoring influences, it 110 becomes apparent that additional trackway elements may be added to control the train when moving in the abnormal direction. In other words, in single track systems where proper control is available for controlling 115 traffic in either direction, both restrictive and restoring track elements with the proper control therefor may be provided on both sides of the track, so that the train may be controlled in accordance with traffic conditions ahead where it is moving in either direction along the trackway.

Conclusion.—The train control system embodying the present invention as illustrated, thus affords means capable of transmitting 120 125 130

a restrictive control influence regardless of the speed of the train which means requires no trackway energy, and in which a restoring influence is capable of being transmitted 5 at all speeds above a predetermined low speed by reason of direct current energy which is only present during the approach and passage of a train under clear traffic conditions ahead; and in which the car-carried 10 apparatus includes car elements disposed on opposite sides of the vehicle which are identical in construction but are connected in circuits so as to function differently, and in which like parts are automatically 15 interchanged when the direction of movement of the vehicle is reversed.

The rectifying device which has been conventionally shown by the audion A has been provided so that a quick acting sensitive 20 and efficient direct current relay may be used in connection with pulsating or alternating current influence receiving apparatus. The employment of this rectifying device is, however, optional and it may be omitted if 25 desired, in which event a similar well balanced alternating current relay may be used. The alternating current used in connection with this apparatus may be derived from any of the well-known methods for producing 30 alternating current from direct current, or may be derived from a suitable alternating current generator such as the generator G illustrated, and preferably is of a comparatively high frequency so as to facilitate 35 the induction of current through an intervening air gap.

Having thus shown and described one specific embodiment of the invention, it is desired to be understood that this has been 40 done for illustrative purposes only, rather than for the purpose of showing the scope of the invention. It is also desired to be understood that various changes and modifications may be made to adapt the invention 45 to the particular problems and systems encountered in practice, without departing from the nature, the scope or the idea or means underlying the present invention.

What is desired to be secured by Letters 50 Patent of the United States is:—

1. In an automatic train control system, the combination of a normally energized control relay on a railway vehicle and means for deenergizing and again restoring said 55 relay from the trackway through an intervening air-gap comprising, an alternating current influence communicating device including a source of alternating current carried on the vehicle and an inert traffic controlled trackway device including a magnetizable core having a coil thereon for transmitting a control influence which will deenergize said relay, a direct current influence communicating device including a 60 track magnet energized under clear traffic 65

conditions ahead by a direct current source located along the trackway, and car-carried means effective when passing by said energized track magnet for restoring said control relay to normal. 70

2. In an automatic train control system, the combination of a normally energized control relay on a railway vehicle and means for deenergizing and again restoring said relay from the trackway through an intervening air-gap comprising, an inductive influence receiving element on the vehicle including a primary, a secondary, and a secondary bucking coil, said secondary coil normally maintaining said control relay energized through a stick circuit, and traffic controlled trackway means for causing the voltage induced in said secondary bucking coil to effectively overcome the voltage induced in said secondary coil under dangerous traffic conditions ahead upon passage thereby, thus deenergizing said relay, and means for restoring said control relay including a pick-up relay adapted to be energized in response to the passage of the vehicle by a track electro-magnet energized by direct current under clear traffic conditions ahead, the picking up of said pick-up relay being due to change of flux caused by movement of suitable vehicle carried means by said electro-magnet. 80 85 90 95

3. Influence communicating means for automatic train control systems comprising, a car-carried core of general inverted U-shape having downwardly extending legs, a primary and secondary coil on one of said legs, a secondary bucking coil on the other leg and connected in series with said secondary coil in a manner so that a change of flux through said core induces opposing voltages in the circuit including said two secondary coils, and traffic controlled trackway means for reducing the reluctance of the magnetic circuit including said coils. 100 105

4. Influence communicating means for automatic train control systems comprising, a car-carried core having a primary and a secondary coil thereon, said primary coil being energized by alternating current, a control relay having a front contact, a rectifying device, an energized circuit for said control relay including the winding and front contact of said relay said rectifying device and said secondary coil, and means partly on the vehicle and partly along the trackway for inducing a voltage in said circuit. 110 115 120

5. Influence communicating means for automatic train control systems comprising, car-carried apparatus including a control relay, a core having two depending legs, a primary and a secondary coil on one of said legs, a bucking secondary coil on the other of said legs connected in series with said secondary coil, means for continuously en- 125 130

ergizing said primary coil by alternating current whereby a voltage is induced in said secondary coil predominating over the opposed voltage induced in said secondary bucking coil, thus producing a current for maintaining said relay energized, and trackway means for deenergizing said relay by increasing the voltage in said secondary bucking coil without materially increasing the voltage in said secondary coil, whereby a system is formed in which a failure of energizing current for said primary coil causes deenergization of said relay.

6. Influence communicating means for automatic train control systems comprising, a car-carried core having a primary and a secondary coil thereon, a control relay, a rectifying device, a circuit including said control relay, said secondary coil and said rectifying device, and means partly on the vehicle and partly along the trackway and including a core of magnetic material along the trackway for reducing the flow of current through said control relay while the car passes by said trackway core.

7. Influence communicating means for automatic train control systems comprising, a car-carried core having a primary coil thereon normally energized by alternating current derived from a car-carried source, a control relay, another coil on said core, a rectifying device, a circuit including the winding of said control relay, said another coil and said rectifying device, means for inducing a voltage in said circuit to maintain said relay energized, and traffic controlled trackway means for inducing a voltage in said other coil to deenergize said relay.

8. In an automatic train control system the combination of restrictive control influence communicating means including a vehicle carried source of alternating current and a coil located on one side of the center line of the vehicle, and a traffic controlled trackway device; a restoring influence communicating means including similar car-carried coils on the other side of center line of the vehicle, and a trackway electro-magnet; circuits for said coils; and means for automatically interchanging the coils in said circuits each time the direction of movement of the vehicle is reversed.

9. Influence communicating means for automatic train control systems of the intermittent type, comprising two separate influence receiving devices carried on opposite sides of the center line of the vehicle, each of said influence receiving devices including a primary coil and two secondary coils connected in series, a source of alternating current for energizing said primary coil, said second coils being so disposed with respect to the primary coil that the flux emitted by said primary coil links one secondary coil more than it does the other secondary coil,

trackway means located on one side of the center line of the trackway effective under adverse traffic conditions ahead to cause a greater increase of the flux linking said one secondary coil than said other secondary coil, train control means in the circuit of said secondary coils, and means for connecting said train control means in the circuit of the secondary coil of the other influence receiving device when the direction of movement of the vehicle is reversed.

10. Influence communicating means for automatic train control systems of the intermittent type, comprising two separate influence receiving devices carried on opposite sides of the center line of the vehicle, each of said influence receiving devices including a primary coil and two secondary coils connected in series, a source of alternating current for energizing said primary coil, said secondary coils being so disposed with respect to the primary coil that the flux emitted by said primary coil links one secondary coil more than it does the other secondary coil, trackway means comprising a core of inert magnetic material when in its active condition and active under adverse traffic conditions ahead for causing flux linking said one secondary coil to be diverted to said other secondary coil, train control means in the circuit of said secondary coils, and means for connecting said train control means in the circuit of the secondary coils of the other influence receiving device when the direction of movement of the vehicle is reversed.

11. Influence communicating means for automatic train control systems of the intermittent type, comprising two separate influence receiving devices carried on opposite sides of the center line of the vehicle, each of said influence receiving devices including a primary coil and two secondary coils connected in series, a source of alternating current for energizing said primary coil, said secondary coils being so disposed with respect to the primary coil that the flux emitted by said primary coil links one secondary coil more than it does the other secondary coil, trackway means effective under adverse traffic conditions ahead for causing flux linking said one secondary coil to be diverted to said other secondary coil, train control means in the circuit of said secondary coils, and means governed in accordance with the rotation of the wheel of the vehicle for connecting said train control means in the circuit of the secondary coils of the other influence receiving device when the direction of movement of the vehicle is reversed.

12. Influence communicating means for automatic train control systems of the intermittent type, comprising two separate influence receiving devices carried on opposite

15. Car-carried influence communicating means for automatic train control systems comprising, two identically constructed influence receiving car elements located equal distances on opposite sides of the center line 70 of a railway vehicle, electrical means normally closed circuited and energized and connected to one of said elements for receiving restrictive control influences, electrical means normally de-energized and connected to the 75 other of said elements for receiving proceed influences, and means for interchanging the connections of said car elements and said electrical means when the direction of movement of the vehicle is reversed. 80
16. Influence communicating means for automatic train control systems, comprising the combination of car-carried apparatus including an influence receiving coil, a relay having a front contact; a rectifying device; 85 and a circuit including a source of energy, said relay, said rectifying device, said coil and said front contact in series; and of trackway means for inducing a voltage in said receiving coil. 90
17. Influence communicating means for automatic train control systems, comprising the combination of car-carried apparatus including an influence receiving coil, a relay 95 having a front contact; a rectifying device and a circuit including a source of energy, said rectifying device, said relay, said coil and said front contact in series; and of an inert magnetizable body of iron located along the trackway for inductively affecting said 100 receiving coil.
18. Car-carried apparatus for automatic train control systems of the intermittent inductive type, comprising a primary coil, two secondary coils connected in series, a source 105 of alternating current for energizing said primary coil, a train control device having two windings one of which is connected in series with said secondary coils and a contact closed when said train control device is energized, said secondary coils being located with respect to said primary coil to cause more alternating flux to link one secondary coil than the other and to cause the flux to induce opposing voltages in the 110 circuit of said secondary coils thereby inducing sufficient current in said one winding of said train control device to maintain it energized, trackway means active under adverse traffic conditions ahead to cause flux 115 linking said one secondary coil to be diverted to link the other secondary coil and cause de-energization of said train control device, and other trackway means effective under 120 clear traffic conditions ahead to produce a flow of current in the other winding of said train control device for restoring it to normal. 125
19. Car-carried apparatus for automatic train control systems of the intermittent in- 130
13. Influence communicating means for automatic train control systems of the intermittent type, comprising two separate influence receiving devices carried on opposite sides of the center line of the vehicle, each of said influence receiving devices including 25 a primary coil and two secondary coils connected in series, a source of alternating current for energizing said primary coil, said secondary coils being so disposed with respect to the primary coil that the flux emitted by said primary coil links one secondary coil more than it does the other secondary coil, trackway means comprising a core of inert magnetic material when in its active condition and active under adverse traffic conditions ahead to cause flux linking said one secondary coil to be diverted to link said other secondary coil, train control means in the circuit of said secondary coils, and means frictionally driven from the wheels 30 of the vehicle for connecting said train control means in the circuit of the secondary coils of the other influence receiving device when the direction of movement of the vehicle is reversed. 45
14. Influence communicating means for automatic train control systems of the intermittent inductive type comprising, a car-carried element having an alternating current electro-motive force induced therein, a coil associated with said element and connected to an electro-responsive device, a rectifying device in the circuit including said coil and electro-responsive device, whereby the electro-responsive device is supplied with undirectional current, and trackway devices located at points along the trackway for changing the flow of current in said circuit while said car-element passes by a trackway device under predetermined traffic conditions ahead. 55

ductive type, comprising a primary coil, two secondary coils connected in series, a source of alternating current for energizing said primary coil, a train control device having 5 two windings one of which is connected in series with said secondary coils and a contact closed when said train control device is energized, said secondary coils being located with respect to said primary coil to cause 10 more alternating flux to link one secondary coil than the other and to cause the flux to induce opposing voltages in the circuit of said secondary coils thereby inducing sufficient current in said one winding of said 15 train control device to maintain it energized, trackway means comprising an inert magnetic body when in its active condition and active under adverse traffic conditions ahead to cause flux linking said one secondary coil 20 to be diverted to link the other secondary coil and cause de-energization of said train control device, and other trackway means effective under clear traffic conditions ahead to produce a flow of current in the other 25 winding of said train control device for restoring it to normal.

20. Car-carried apparatus for automatic train control systems comprising, a control relay having two windings and a front contact, means for energizing a circuit including one of said windings and said front contact in series comprising an alternating current source and a rectifier, and means responsive to control influences transmitted 30 from the trackway for energizing the other winding upon the reception of a control influence.

21. Car-carried influence communicating means for automatic train control systems 40 comprising, two identically constructed influence receiving car elements located equal distances on opposite sides of the center line of a railway vehicle; a control relay having a front contact; a circuit including a source 45 of energy, the winding and front contact of said relay, and one of said receiving elements in series; a reset relay; another circuit including the other influence receiving element and the winding of said reset relay 50 in series; and means for interchanging the influence receiving elements in said circuits if the direction of movement of the vehicle is reversed.

22. Car-carried influence communicating 55 means for automatic train control systems comprising, two identically constructed influence receiving car elements located equal distances on opposite sides of the center line of a railway vehicle; a control relay having 60 a front contact; a circuit including a source of energy, the winding and front contact of said relay, and one of said receiving elements in series; a reset relay; another circuit including the other influence receiving 65 element and the winding of said reset relay

in series; and a switch operated upon the reversal of the direction of rotation of the wheels of the vehicle for interchanging said influence receiving elements in said circuits.

23. Car-carried apparatus for automatic 70 train control systems of the intermittent inductive type, the combination of two substantially identically constructed influence receiving car elements each comprising a core having two coils thereon, restrictive 75 control mechanism including two circuits one of which energizes one of the coils of one of the influence receiving car elements and the other of which includes a relay and the other coil of said influence receiving car 80 element, proceed control influence mechanism including a reset relay and both coils of the other influence receiving element, and means for interchanging the influence receiving elements in said mechanisms if the 85 direction of movement of the vehicle is reversed.

24. Car-carried apparatus for automatic 90 train control systems of the intermittent inductive type, the combination of two substantially identically constructed influence receiving car elements each comprising a core having two coils thereon, restrictive 95 control mechanism including two circuits one of which energizes one of the coils of one of the influence receiving car elements and the other of which includes a relay and the other coil of said influence receiving car element, proceed control influence mechanism including a reset relay and both coils 100 of the other influence receiving element, and a switch operated upon the reversal of the direction of rotation of the wheels of the vehicle for interchanging said influence receiving elements in said mechanisms.

25. Car-carried influence communicating 105 means for automatic train control systems comprising, two identically constructed influence receiving car elements located symmetrically with respect to the center line of 110 a railway vehicle, electrical means normally closed circuited and energized and connected to one of said elements for receiving restrictive control influences, electrical means normally de-energized and connected to the other of said elements for receiving proceed influences, brake control apparatus initiated by the first mentioned electrical means and restored by the second mentioned electrical means, and means for interchanging the connections of said car elements and said electrical means when the direction of movement of the vehicle is reversed.

26. Car-carried influence communicating 115 means for automatic train control systems comprising; two identically constructed influence receiving car elements located equal distances on opposite sides of the center line 120 of a railway vehicle; a control relay having a front contact; a circuit including a source of energy, the winding and front contact of said relay, and one of said receiving elements in series; a reset relay; another circuit including the other influence receiving 125 element and the winding of said reset relay

source of energy, the winding and front contact of said relay, and one of said receiving elements in series; a reset relay; another circuit including the other influence receiving element and the winding of said reset relay in series; brake control apparatus governed by said control relay, and means for interchanging the influence receiving elements in said circuits if the direction of movement of the vehicle is reversed. ¹⁰
